PROCESS OF ELIMINATING ARSENIC COMPOUNDS FROM PHOSPHORIC ACID

Franz Rodis and Helmut Klee, Knapsack, near Köln, Germany, assignors to Knapsack-Griesheim Aktiengesellschaft, Knapsack-Bezirk Köln, Germany, a company of Germany

Application August 31, 1954, Serial No. 453,295

Claims priority, application Germany September 2, 1953

5 Claims. (Cl. 204—130)

The present invention relates to a process of eliminating arsenic compounds from phosphoric acid by electrolysis. For this process there come into consideration phosphoric acids with a content of about 20 percent to about 95 percent of H_3PO_4 , preferably with a content ranging between 50 percent and 90 percent of H_3PO_4 .

The time required for the electro-deposition of arsenic from phosphoric acid containing arsenic compounds is extraordinarily long as compared, under otherwise the same conditions, with the electro-deposition of other metals having the same place in the electrochemical series. It is known to use copper as cathode and platinum as anode and a cathodic current density of not more than 1 ampere per square decimetre or to accelerate the electro-deposition of arsenic from phosphoric acid by the simultaneous electrodeposition of copper. When using this method of working a ratio of the contents of copper and arsenic in the acid of 1 to at least 2, or better still of 1:2.5 to 1:4, is advantageously used. Examinations showed, however, that the arsenic concentrations in the phosphoric acid, under otherwise the same conditions, continuously decrease with increasing additions of copper ions. Satisfactory results are only obtained if about 5 to about 10 times as many copper ions as arsenic are present in the acid.

The present invention is based on the observation that arsenic compounds are deposited by electrolysis from phosphoric acid by operating with addition of copper compounds and by depositing the arsenic compounds by the action of iodine during the electrolysis in the form of arsenic. It was found that small amounts of iodine, i. e. a few milligrams per kilogram of acid, increase the speed of deposition of arsenic from phosphoric acid in an extraordinary and sudden manner. It is of advantage to operate at the commencement of the deposition with a proportion by weight of arsenic to copper in the phosphoric acid ranging from about 1:about 0.2 to about 1:about 5 as well as with a proportion by weight of copper to iodine ranging from about 100:about 0.5 to about 100:about 50. It has proved of special advantage to maintain the proportion by weight of copper to iodine at a value ranging between 100:2 and 100:15. The operation is advantageously carried out while stirring and at temperatures ranging between about 60° C. and about 250° C., preferably between 60° C. and about 150° C.

The desired iodine content can be attained by adding an aqueous iodine solution to the phosphoric acid or by working in such a way that iodine is formed from iodides during the reaction. As iodides there come into consideration, in addition to CuI , all soluble iodides such as NaI , KI , NH_4I , CaI_2 , BaI_2 , SrI_2 , MgI_2 . Hydriodic acid may also be used.

As copper compounds are suitable all soluble copper salts either as such or in solution, the anionic component of which does not have a disturbing effect regarding the purity of the phosphoric acid. There are mentioned, for instance, $CuCl_2$, $CuSO_4$, $Cu(NO_3)_2$, $CuBr_2$, Cu -acetate.

2

The use of Cu -phosphate is of special advantage but CuI may also be used as was already mentioned.

The examples given further below show that a phosphoric acid which is practically free from arsenic is obtained when working with an arsenic concentration of 40 milligrams per kilogram of acid and with an iodine concentration of about 1.8 milligrams per kilogram of acid. The copper ions are deposited on the cathode and are no longer detectable in the phosphoric acid after the electrolysis.

When copper ions are added in the form of copper sulfate, merely the sulfate anion of the copper sulphate remains in the phosphoric acid. If one wants to avoid this, copper phosphate must be added straight away or the necessary quantity of copper must be dissolved in the required quantity of phosphoric acid at the anode.

The addition of iodine should advantageously be kept in its limits since otherwise the elimination of arsenic is deteriorated as is shown by the following table

20

25

30

35

40

45

50

55

60

65

70

	Addition to phosphoric acid		Content of arsenic in the phosphoric acid, mgs./kg. of acid
	Cu ions, mgs./kg. of acid	Iodine, mgs./kg. of acid	
untreated phosphoric acid			40
40	0.6	3	
40	1.2	1	
40	1.8	0	
40	3.0	5	

From the above table can be seen that, when reducing the addition of iodine from 1.8 to 0.6 milligrams per kilogram of acid, the content of arsenic rises again from practically zero to 3 milligrams per kilogram of acid. When raising the addition of iodine from 1.8 to 3 milligrams per kilogram of acid the content of arsenic in the phosphoric acid rises likewise from practically zero to 5 milligrams per kilogram of acid.

An increase of the copper ions is likewise detrimental. Using a content of 1.8 milligrams of iodine per kilogram of acid and increasing the additions of copper ions from 40 to 68 and then to 112 milligrams, the arsenic content rises from practically zero to 3 milligrams per kilogram of phosphoric acid.

The process according to the present invention is illustrated in the accompanying diagrammatic drawings. Figure 1 represents a side elevation of the apparatus, Figure 2 represents a top view.

40 milligrams of copper ions per kilogram of acid in the form of a very concentrated solution of copper salt and 1.8 milligrams of iodine per kilogram of acid in the form of an aqueous 0.1N-solution of iodine are added to the phosphoric acid which contains arsenic. The whole is passed through the tube 4 into a double-walled vessel 3 which has an acid-proof brick lining and which is provided with a supply pipe 1 and a drain pipe 2 for the heating liquid and is then heated to about 90° C. by means of the heating liquid. The electric current required for the electrolysis is supplied over the anode 7 having a cylindrical shape and consisting of a platinum wire gauze and over the cathode 8 being likewise of a cylindrical shape and consisting of a copper wire gauze. The stirrer 6 effects the thorough mixing of the reaction mixture. On termination of the electrolysis which takes place under a tension of about 3 volts and at an amperage of about 5 amperes, the phosphoric acid which is now free from arsenic leaves the electrolytic vessel 3 through the outlet 5. Supply and discharge of the phosphoric

acid are regulated in such a way that the acid is subjected to electrolysis for about 30 minutes.

The process may also be carried out discontinuously. The following examples serve to illustrate the invention but they are not intended to limit it thereto:

Example 1

3 litres of phosphoric acid (80-85 percent), which contain 40 milligrams of arsenic per kilogram of acid in the form of arsenic compounds, are heated to 90° C. and stirred by means of a stirrer (3-5 revolutions per second). Into this phosphoric acid are placed as cathode two copper wire gauzes of cylindrical shape which are inserted into each other, and have a height of 13 cms. and a diameter of 4 and 13 cms. respectively. Between the 2 copper wire gauzes a platinum wire-gauze electrode is placed as anode. 40 milligrams of copper ions per kilogram of acid in the form of an aqueous copper sulfate solution as concentrated as possible and 1.8 milligrams of iodine per kilogram of acid in the form of an aqueous 0.1 N-solution of iodine are added and the acid is electrolyzed under 3 volts and at 5 amperes. After about 30 minutes the acid is free from arsenic.

Example 2

3 litres of phosphoric acid (80-85 percent) which contain 40 milligrams of arsenic per kilogram of acid in the form of arsenic compounds are heated to 90° C. and stirred by means of a stirrer. The arrangement of the electrodes is the same as described in Example 1. 40 milligrams of copper ions per kilogram of acid in the form of an aqueous copper sulfate solution as concentrated as possible and 1.8 milligrams of iodine per kilogram of acid in the form of an aqueous 0.1 N-potassium or sodium iodide solution are added and the acid is electrolyzed under the same conditions as described in Example 1. A phosphoric acid which is free from arsenic is obtained.

Example 3

3 litres of phosphoric acid (80-85 percent) which contain 40 milligrams of arsenic per kilogram of acid in the form of arsenic compounds are heated to 90° C. and stirred by means of a stirrer. The arrangement of the electrodes is the same as described in Example 1. 40 milligrams of copper per kilogram of acid in the form of dry copper phosphate and 1.8 milligrams of iodine per kilogram of acid in the form of an aqueous 0.1 N-iodine solution are then added and the acid is electrolyzed as described in Example 1. A phosphoric acid which is free from arsenic is obtained.

Example 4

3 litres of phosphoric acid (80-85 percent) which contain 40 milligrams of arsenic per kilogram of acid in the form of arsenic compounds are heated to 90° C. and stirred by means of a stirrer. The arrangement of the electrodes is the same as described in Example 1. 40 milligrams of copper per kilogram of acid in the form

of dry copper phosphate and 1.8 milligrams of iodine per kilogram of acid in the form of an aqueous 0.1 N-solution of potassium or sodium iodide solution are added and the acid is electrolyzed under the same conditions as described in Example 1. A phosphoric acid which is free from arsenic is obtained.

We claim:

- 10 1. A process of eliminating arsenic compounds from phosphoric acid by electrolysis, in which the electrolysis is carried out with a phosphoric acid which, at the commencement of the deposition, contains arsenic and copper in a proportion by weight ranging from between about 1:about 0.2 to about 1:about 5, and copper and iodine in a proportion by weight ranging from between about 40:0.6 to 40:3.0.
- 15 2. A process of eliminating arsenic compounds from phosphoric acid by electrolysis, in which the electrolysis is carried out with a phosphoric acid which contains a soluble copper salt in such a quantity that, at the commencement of the deposition, the proportion by weight of arsenic to copper ranges from between about 1:about 0.2 to about 1:about 5, and which contains iodine in such a quantity that the proportion by weight of copper to iodine ranges from between 40:0.6 to 40:3.0.
- 20 3. A process of eliminating arsenic compounds from phosphoric acid by electrolysis, in which the electrolysis is carried out with a phosphoric acid which, at the commencement of the deposition, contains arsenic and copper in a proportion by weight ranging from between about 1:about 0.2 to about 1:about 5, and in which an iodine solution is added to the phosphoric acid in such a quantity that the proportion by weight of copper to iodine ranges from between about 40:0.6 to 40:3.0.
- 25 4. A process of eliminating arsenic compounds from phosphoric acid by electrolysis, in which the electrolysis is carried out with a phosphoric acid which, at the commencement of the deposition, contains arsenic and copper in a proportion by weight ranging from between about 1:about 0.2 to about 1:about 5, and in which the desired iodine content is attained by the formation of iodine from iodides during the reaction, these iodides being added to the phosphoric acid in such a quantity that copper and iodine are present in a proportion by weight ranging from between about 40:0.6 to 40:3.0.
- 30 5. A process of eliminating arsenic compounds from phosphoric acid by electrolysis, in which the electrolysis is carried out with a phosphoric acid which, at the commencement of the deposition, contains arsenic and copper in a proportion by weight ranging from between about 1:about 0.2 to about 1:about 5, and in which the desired iodine content is attained by the formation of iodine from hydriodic acid during the reaction, the hydriodic acid being added to the phosphoric acid in such a quantity that copper and iodine are present in a proportion by weight ranging from between 40:0.6 to 40:3.0.
